ATTORNEY

UNITED STATES PATENT OFFICE

WILLIAM S. SMITH, OF PORT MOODY, BRITISH COLUMBIA, CANADA

SAWING CARRIAGE

Application filed October 25, 1930. Serial No. 491,276.

This invention relates to a device for the manufacture of the product of United States Patent No. 1,593,800, whereby the product may be manufactured economically in commercial quantities.

This invention is designed as an improvement in sawing devices and is intended to be an auxiliary to standard sawing equipment.

10 An object of the invention has been to provide in simple form and manner a device versatile in character and capable of handling a wide range of material as to thickness and length.

15 Still another object of the invention has been to provide in a device of this character the necessary rigidity and flexibility requisite as owing to the character of the material worked with great variations may be found 20 therein, so that it is necessary to provide flexibility in the equipment and means to make rigid instantaneously the flexible parts before operating upon the material with the saw.

To the attainment of the foregoing objects 25 I have invented the new and novel construction more specifically described in the following specification and illustrated by the accompanying drawings, in which:

Figure 1 is a plan view of my invention.

30 Figure 2 is a part sectional view and elevation of one of the bell crank levers and vertical angle members.

Figure 3 is an elevational view of bell 35 crank lever and vertical angle member with board held therebetween for sawing purposes.

In these drawings like numerals indicate like parts and 5 indicates a board slidable between parallel guides 6 positioned upon the table 7 of a band saw 8 and slidable past 40 the saw. Down the centre of the board and starting from one end is the saw slot 9 for the saw to operate in and this slot is closed at its starting end by a transverse block 10 secured to the board 5 by wing nuts and bolts 11, 45 thereby providing reinforcement to the board 5.

Positioned on the slidable board and on each side of the saw slot 9, but spaced apart, 50 are upright angle brackets 12 having a slot 13 in the base thereof and secured to the board

5 by bolt and nut 14, the slot 13 providing a limiting adjusting range to the brackets 12. The vertical uprights of the brackets 12 are faced with wooden facings 15 secured thereto by the bolts and nuts 16.

Opposite the brackets 12 and on the opposite side of the slot 9 are positioned bell crank levers 17 pivoted at 18 and having upturned ends 19.

The upturned ends 19 opposite the angle brackets 12 have metal face pieces 20 secured thereto by a loosely fitted bolt 21 whose head is heavily countersunk in the face piece 20.

Below the bolt 21 is a helical compression spring 22 set in the recess 23 formed in the upturned end 19.

The spring 22 holds apart the face member 20 from the bottom of the upturned end 19, thereby assuring a positive grip over the 70 whole width of any board placed between the angle bracket 12 and the bell crank levers 17 and permits boards of uneven thickness to be held securely.

The top end of the upright 19 is slightly rounded at 24 and this permits of a rocking motion of the face member 20 through the loosely fitted bolt 21.

Positioned at one end of the slidable board 5 is the lever 25 pivoted on the bolt 26 to the centre of the board 5 and having a handle 27 on one end. Pivoted to the lever 25 are the rods 28 passing through holes 29 in the arms of the bell crank levers 17 and having the compression springs 30 on each side of the lever arm mounted upon the rods 28 and secured there by the nuts 31.

Movement of the handle 27 of the lever 25 causes the bell crank levers 17 to move to or from the faces of the fixed angle members 12 in unison and enables a board to be gripped therebetween for sawing purposes and be traversed past the saw by the slidable board 5.

Having now described my invention, what I claim and desire to be protected in by Letters Patent, is:

1. In a device of the character described the combination comprising a sawing machine, a board slidable between parallel guide members and by the saw of said sawing machine, said board having a slot down the cen- 100

ter from one end thereof for the reception of a saw therebetween, said slot being closed at its starting end by a transverse clamp member suitably secured to said slidable board, said board having positioned and spaced apart thereon a pair of levers and a pair of vertical angle members, said angle members having vertically positioned face members secured thereto, said levers having one end upturned, face members held apart from said upturned ends, means rockably securing said last named face members to the respective upturned ends of said levers, and yieldable means interposed between said last named face members and their respective levers' upturned ends, said last named face members being opposite to said vertical angle members to grip and hold a board therebetween for sawing, and means to operate said levers in unison.

2. In a device of the character described, the combination comprising a sawing machine, a board slidable between parallel guide members and by the saw of said sawing machine, said board having a slot down the centre from one end thereof for the reception of a saw therebetween, said slot being closed at its starting end by a transverse clamp member secured to said slidable board by bolts and wing nuts, said board having positioned and spaced apart thereon a pair of bell crank levers and vertical angle members, said angle members having vertically positioned wooden face members secured thereto, said bell crank levers having one end upturned, said upturned ends having a bolt passing therethrough, said bolt carrying a face member held apart from said upturned ends by a helical spring, said face member being opposite to said vertical angle member to grip and hold a board therebetween for sawing, and means to operate said bell crank levers in unison, said means comprising a pair of rods and a handled lever pivotally engaged to said rods and thereby said bell crank levers, and said slidable board whereby said bell crank levers are caused to move to or from said vertical angle members, when said handled lever is moved.

50 In testimony whereof I affix my signature.
WILLIAM S. SMITH.
